PROCESS OF AND APPARATUS FOR THE DEVELOPMENT OF VOLATILES FROM HYDROCARBON SUBSTANCES

Louis J. Walsh, Belmont, Mass.

Application May 5, 1926, Serial No. 106,873

4 Claims. (Cl. 196—49)

This invention relates to treating mineral hydrocarbons to produce gasoline, and to produce other hydrocarbons susceptible of use as cycle stock for re-treatment in the process, and of 5 other uses.

Objects of the invention are to improve the efficiency of heat treatment in liquid phase as measured by the rate of cracking or conversion of material treated during a unit of the time the 10 material is kept under cracking or conversion conditions; to increase the proportion of gasoline volatiles obtained at each passage through cracking apparatus of the material treated; to obtain the said results with a minimum production of 15 undesirable end products such as fixed gases and free carbon; to reduce the amount of fuel required to produce a unit quantity of gasoline volatiles; and to reach these results by steps capable of performance in simple and safe apparatus 20 having no large vessels containing oil under high pressures at high temperatures; and to provide apparatus of the said characteristics.

One of the objects of this invention is to avoid treatment by heat of hydrocarbon material already containing more than a critical proportion 25 of cracked volatiles, for the purpose and with the result of facilitating the rapid development of cracked volatiles at moderate degrees of heat, with the end results of a maximum development 30 of cracked volatiles in relation to the degree of heating, avoidance of any undue production of fixed gases, tar or coke, and maximum development of volatiles in relation to the volume of oil retained in the treatment apparatus.

Practices according to the invention include treatment of liquid hydrocarbon materials by subjecting the materials to successive increments of increase of temperature and/or decrease of pressure, with intermediate alternate recessions 40 of temperature and/or pressure, or both, and concomitantly withdrawing, upon each recessional stage of treatment, a fractional portion of the charge corresponding substantially to the volatile fraction produced under the conditions of a preceding stage of treatment. Practice of the 45 invention further includes causing the non-volatilized fraction or residue of the treated oil to be recovered at each stage of treatment in a condition susceptible of further continued thermal 50 treatment and conversion and in a state free from undue gummy inclusions and carbon. Ancillary features of the procedure recommended include conservation of attained heat and maintenance of volume under treatment, for example by the 55 concurrent addition of fresh hydrocarbon ma-

terial or cycle stock to the hydrocarbon material during or after each stage of withdrawal of volatiles and of temperature and/or pressure recession, to make up volume substantially to compensate for a fraction removed in a vaporized 60 condition. The process thus provides for continuity of treatment, conserves heat, and reaches a high thermal efficiency.

A typical instance of practice of the invention will now be described as carried out upon crude 65 petroleum as the initial charging stock, as an example only of a process according to the invention. In the accompanying drawing:

Fig. 1 is a diagrammatic flow sheet and elevation partly in section of suitable apparatus; and 70

Fig. 2 is a curve plotted in relation to Fig. 1 illustrating a typical sequence of temperature changes.

The steps of the treatment may be practiced by preliminary heating of the raw material entering the apparatus through a pipe 1; separation or topping of the material, a preliminary cracking treatment, a temperature-pressure reduction and withdrawal of volatiles as vapor; a second cracking treatment, a second temperature-pressure reduction, and withdrawal of volatiles as vapor; a third cracking treatment, a third temperature-pressure reduction and withdrawal of volatiles as vapor; further stages of cracking, if desired, with temperature-pressure reduction and withdrawal of volatiles; return of the unvolatilized hydrocarbon from the last cracking treatment to the topping or separation step in the process; selective reflux fractionation, and condensation of the withdrawn vapors; and withdrawal of fractions of the volatiles to storage; and fractionation and condensation of part of the material for further cracking treatment or passage to storage.

The apparatus illustrated comprises a feed 95 pump 2 delivering to a feed line 3 and through heat exchangers 4, 5 and 6 to a preheater 7, which may be any suitable pipe coil in a furnace 8, and thence through valved connections 9, 10, alternatively or concurrently to a topping 100 still 12 or a vaporizer tank 13. But any part of the effect of the heating devices 4, 5, 6 or 7 may be dispensed with on occasion, for example when the feed-stock is a material already deprived of natural volatiles, and for this purpose 105 valved by-passes 15 from pump 2 to feed line 3 and 16, to provide a shunt around preheater 7, may be used to carry all or a portion of the flow from pump 2.

If the material contains volatiles of the gaso- 110

- line range, it is desirable to separate these before the remainder of the treatment, and for this purpose the topping still 12, sufficiently heated (by furnace 14, and/or furnace 8, and/or heat exchangers 4, 5 and 6) receives the flow from pipe 3 in the first instance. A vapor pipe 11 from still 12 leads to a primary fractionation tower 20, from which the bottom condensate may return to still 12 through a valved pipe 27 or be returned to vaporizer 13 through a valved pipe 27a. The tower 20 may be the primary tower for fractionation of cracked volatiles also, as presently mentioned. Preferably the tower 20 operates in relation to a secondary tower 21 from which the bottom condensate may also flow through a valved pipe 17 to still 12. Still 12 may therefore be operated, when not receiving material to be topped from pipe 3, as a heater for maintaining the rectifying operation of tower 20 or 21, or both. Still 12 may also be operated as a storage receiver for material which it is desired to pump through the cracking stage of the apparatus.
- If the material to be cracked contains portions of the asphaltic range it may be desirable to separate these before the remainder of the treatment, and for this purpose the vaporizer tank 13, sufficiently heated by furnace 14, or preceding heaters, receives the flow from pipe 3 in the first instance. A vapor pipe 56 from vaporizer 13 leads to primary fractionation tower 20, from which the bottom condensate may return to still 12 through pipe 27. The portions of the asphaltic range remain in the liquid state and are drawn off through valve 57 and cooler 58 to storage. The uncondensed vaporous efflux from tower 20 may pass over to tower 21 by pipe 19 through a reflux condenser, which may comprise one side of each of the feed line heat-exchangers 5 and 6. Tower 21 may have a reflux condenser comprising one side of the heat-exchanger 4, operating at a lower temperature than the heat-exchangers and condensers 5 and 6. Vapors passing the exchanger 4 through pipe 22 are the more volatile fraction of the output of this process, preferably are condensed in the water condenser indicated at 24, and the liquid product flows to storage in the gasoline tank 25 through pipe 26.
- The topped, untopped and/or separated hot material flowing through still 12, and recycled material from valved pipes 27 and 17 and, when desired, liquid from vaporizer tank 13 flowing through a valved pipe 29, comprise together or severally treatment stock to be cracked for optimum development of gasoline-range volatiles according to this process. For this purpose the pipe 28 delivers to a hot oil pressure-feed pump 30 delivering to a pipe 31 leading its flow in series through any desired number, shown as three, of cracking units, preferably made as long convoluted pipe coils 33, 34, 35 adapted to be heated in independently regulated furnaces 36, 37, 38 respectively.
- Bearing in mind that the pump 30 delivers a relatively hot feed stock in the pipe line 31, the cracking unit 33, 36 (and succeeding units in turn) may be relied upon to carry the temperature of the oil in liquid phase to selected maximum cracking temperature, optimum for the material being treated, its rate of flow, and the pressure imposed upon it, to produce at the end of the primary cracking unit 33, 36, a content of gasoline volatiles appropriate to the length of flow in the coil 33 and the temperature; that is to say, a proportion of developed volatiles from the heat treatment according to a preferred step in the process, which is to produce in and of the material treated not to exceed from 10 to 15% by volume of developed volatiles included in the heated stream of material at any place in the series of steps of the treatment.
- The purposes of this limitation upon the development of volatiles include avoidance of premature development of vapor in the coil 33, having regard to the pressures and temperature. This, in turn, results in an exchange of heat of high efficiency between the furnace 36, through the walls of the coil 33 to the liquid oil, which is in agitated flow because of the convoluted coil 33. Moreover, it is observed and relied upon that the presence of more than 10 to 15% of developed gasoline volatiles is inhibitory to the further development from the fluid containing this percentage of any further proportion of gasoline volatiles. While the causes of this phenomenon are obscure, the fact is that the heat treatment of a petroleum fraction, containing no cracked volatiles, results in the first stage of treatment in a much faster development of the desirable range of volatile products than it does at a later stage, if nothing has been done to strip the reacting volume of oil of its volatile inclusions.
- It is therefore recommended that the respective cracking units be connected in series by pipes 40, 41, etc., in which respectively (depending upon the number of cracking units) are interposed intermediate vaporizing chambers 45, 46, etc., the flow in series through the cracking units passing through the chambers 45 and 46 and from the final cracking unit 35, 38, passing by the educt pipe 42 and pressure-reducing valve 43 to the vaporizing tank or receiver 13 above mentioned.
- The intermediate vaporizers 45, 46, are preferably of sufficient capacity to permit their contents to act as relatively still pools in the stream under rapid flow at other points in the system; regarded as a part of the flowing stream, their contents undergo a recession of temperature, which may be the consequence of reduced pressure or of admixture with cooling material; or, particularly, the effect of vaporization at a slight reduction of pressure of the vapors of the volatile substances and gases produced by heat in the preceding stage of heat treatment.
- Referring to Fig. 2, which plots in coordinate relation with Fig. 1 the attained temperatures, temperature at exit from the first cracking unit 33, 36, may have reached a point, chosen in relation to the material and the pressures, between 840° and 900° F., but during stay in the intermediate vaporizer 45 these temperatures drop materially, for example through about 10° F., so that if the attained temperature is 840° the temperature in the vaporizer 45 may be about 830°; and if the temperature at exit from coil 33 is 900°, the temperature in vaporizer 45 may be about 890°. The vapor effluent from the material in the vaporizer 45 flows away through the valve 48 and the manifold vapor pipe 50 to the bottom of the tower 20.
- The loss to vapor in the vaporizer tank 45 will reduce the volume of the contents flowing in the system unless compensated for. This loss is therefore made up or exceeded by the injection of fresh feed stock from the pressure feed pipe 31 through a valve 52. A similar pipe 53 and valve 54 may also be provided for the intermediate vaporizer 46 and any further intermediate

vaporizers in the system. Regulation of the valves 52, 54, may be depended upon not only to make up the volume but sensitively to affect the temperature in the respective vaporizers 5 through regulation of the admission of comparatively cool oil under comparatively high pressure from the pipe 31.

Referring again to Fig. 2, the second cracking unit 34, 37, may be operated either slightly to increase or merely to maintain the educt temperature of the liquid oil flowing from the preceding separator 45. This material, having lost substantially all of its volatile contents in the vaporizer 45, is, in respect to volatile contents, 10 in the same fresh condition as the material running to the primary cracking unit 33, 36, and cracking to produce another ten to fifteen per centum of volatiles may proceed at the attained 15 temperature at exit from vaporizer 45 with high 20 efficiency.

The operation of stripping the volatiles from the cracked material from the secondary unit 34, 37, may be now carried out in the intermediate vaporizer 46, exactly as described in 25 connection with vaporizer 45, except that a drop of temperature, which may be substantially through 10° F. of attained temperature will now bring the material to temperatures ranging about 20° F. below the temperature at exit from the 30 primary cracking unit 33, 36. Assuming that educt from the vaporizer 46 is at a temperature within the range of from 820° to 880° F., the tertiary cracking unit 35, 38, may be operated to bring up the temperature again to the 35 temperature at exit from the secondary unit 34, 37; that is to say, in the described instance to temperature respectively ranging from 830° to 40 890° F. Vapors from the vaporizer 46 flow into the manifold 50 through a pipe connection having a valve 55.

There may be as many cracking units 33, 36; 34, 37; 35, 38; as are suitable to the optimum development from the material at a single run of the desired percentage of gasoline volatiles.

45 The three cracking units shown are by way of example only.

Whatever the number of cracking units the educt pipe 42 delivers the hot material from the last of them to the larger vaporizer tank 13 in 50 which it is preferred to permit a drop of temperature to about 650° F. as indicated in Fig. 2. The thoroughly evolved vapor at this temperature from the tank 13 is carried away by the pipe connection 56 to the bottom of the tower 20.

55 From time to time the non-volatile bottoms of the vaporizer tank 13 may be led away through the valved connection 57 and the cooling coil 58 to storage. This residue is useful as a fuel oil. Sometimes a flow of cycle stock from the tank 60 13 is maintained through the pipe 29 and the pump 30, as mentioned above.

As mentioned above, the delivery of the gasoline volatiles from the rectifying towers 20, 21, is through the condenser 24 and pipe 26 to the tank 25. The material in the bottom of the tower 65 21 may vary, in accordance with the degree of the treatment, the nature of the original feed stock and other factors, through the boiling point ranges of kerosene, gas oil or high boiling 70 gasoline. So much of this material as it is not desired to return through the still 12 may be cooled at the cooler 59 and flow to a storage tank 60 for this heavy distillate.

75 It will be obvious that the material supplied to the pipe 1 may be either crude petroleum or a

distillate substance; as above described the degree of preheating at 4, 5, 6 and 7 may be controlled, or preheating may be avoided by the use of the by-passes 15 and/or 16, all of the preheating then occurring in the still 12, which may serve as a primary heater for a distillate or topped crude, and as a source of re-vaporizing heat for the proper operation of the column 20. If desired, any proportion of the incoming relatively cool charging stock may be delivered through the valve 9 into the vaporizer tank 13 to aid in a suitable reduction of temperature at this point.

It will be obvious that the primary pressure in the cracking unit 33, 36 and in the pipe 31 is a function of the rate of the pump 30, and that the desirable value of this pressure has relation to the temperature at which the furnaces 36, 37, 38 are operated and the hydraulic resistance of the pipe system of the cracking units to flow; these factors of relationship of pressure and temperature are in turn determined by the nature of the material being treated and the desired degree of development of the gasoline volatiles. When the initial cracking temperature reaches 100 the range of from 840° to 900° and the material is a crude oil, the typical initial pressure in the line 31 is about 700 lbs. per square inch; but this value is highly variable in practice, and should be so, to enable the result obtained of holding to 105 liquid phase the flow in the successive cracking units. Naturally, the pressure in the second cracking unit is a lesser pressure, preferably by about 50 to 75 lbs. to the square inch; this pressure is measured by the pressure at which the 110 vaporizer 45 at the attained temperature of the oil operates to permit vaporization of all or substantially all of the developed volatiles and gases. The further stages of the process operate under the same system of relationships, loss of hydraulic head of about 50 to 75 lbs. to the square 115 inch at each cracking unit reducing the pressure toward the end of the system, and being controlled by adjustment at valve 43, which is preferably so adjusted as to cause pressure in vaporizing tank 13 of about 50 lbs. to the square inch only above atmospheric pressure, having regard to the pressure in tank 13 imposed by the resistance to flow through columns 20 and 21 and resistance beyond, including adjustment of flow at 120 valve 61 and valve 62. Intermediate pressure-reducing valves 63, 64 may, if desired, be provided between each stage of cracking further to control the loss of hydraulic head from stage to stage of the treatment. A typical operating pressure at valve 43 is 550 lbs. above atmosphere.

The pressures in the rectifying columns 20, 21, may be suitably controlled at valves 61 and 62.

It will be observed that at sundry places in this process, for example in the separators or 135 vaporizers 45, 46 and 13, the vapors of the more volatile substances in the flow are permitted to separate according to their vapor pressures, the pressure against flow from the container of the volatile substances and the temperature at that point.

The imposed pressure and the temperature are factors of a condition permitting volatilization, the same results following when the temperature and pressure are higher, or when the temperature and pressure are lower. An expression for the integrated value of temperature and pressure when there is flow off of vapor is, within limits, a measure of potential in relation to any resistance against which a volatile 140 of any particular vapor-pressure will flow off, and 150

when I refer in the claims to "temperature-pressure potential" I allude to this condition, whichever of its component factors is relatively high or low.

5 I claim:

1. Apparatus for cracking heavier hydrocarbon oils to produce gasoline having in combination a series of tubular heaters and means for causing liquid flow through them in series under initial

10 pressure, a series of intermediate vaporizers in series in said flow and severally between said heaters, and means for shunting a part of the liquid flow under initial pressure into each of said intermediate vaporizers.

15 2. In apparatus for the cracking of oil, the improvement which comprises a separator connected to receive the hot cracked product, pipes for separately withdrawing vapors and tar from the separator, heat exchange means for condensing heavier vapors by indirect cooling, an accumula-

20 tor, means for conveying the condensed heavier vapors to the accumulator, a fractionating tower, a pipe for conveying vapors from the heat ex-

25 change means to the fractionating tower, a pipe for conveying condensate from the fractionating tower to the accumulator, means for condensing a vaporous product of the fractionation, a pipe for supplying fresh oil to be cracked to the accumu-

30 lator, and a pipe for conveying the mixed oils from the accumulator to the cracking equipment.

3. A process for cracking heavier hydrocarbon

oils to produce gasoline, comprising cracking a liquid hydrocarbon oil under high initial pressure in an elongated cracking zone so as to form not substantially more than 10%-15% of gasoline volatiles therein, passing the cracked oil into a vaporizing zone, dropping the pressure through said zone by not more than 50-75 lbs. per sq. in., removing from the vaporizing zone substantially all the gasoline and more volatile hydrocarbons, passing the remaining oil as a liquid into a second elongated cracking zone, subjecting the oil in such second cracking zone to cracking conditions of temperature under pressure less than in the first cracking zone by not more than about 50-75 lbs. per sq. in. to form not substantially more than 10%-15% of gasoline volatiles in the oil, passing the oil cracked in said second cracking zone into a second vaporizing zone maintained under conditions to permit evolution of the gasoline volatiles therefrom, and segregating such gasoline volatiles and the residual oil.

4. Method according to claim 3 in which the residual oil from the second vaporizing stage is again cracked so as to produce not substantially more than 10%-15% of gasoline volatiles, and is then discharged at lower pressure and temperature into a vaporizing zone from which the gasoline volatiles are recovered and the residual oil removed.
